DESIGN FOR AN ANIMAL TRAP

William A. Uttz, Sr., Fort Worth, Tex., assignor
to H. L. Collins, Sr., Fort Worth, Tex.

Application August 13, 1938, Serial No. 79,311

Term of patent 14 years

To all whom it may concern:

Be it known that I, William A. Uttz, Sr., a citizen of the United States, residing at Fort Worth, in the county of Tarrant and State of Texas, have invented a new, original, and ornamental Design for Animal Traps, of which the following is a specification, reference being had to the accompanying drawing, forming part thereof.

Fig. 1 is a plan view of the trap, showing my new design.

Fig. 2 is a side elevation of the trap.

Fig. 3 is a perspective view of the trap.

I claim:

The ornamental design for an animal trap, as shown.

WILLIAM A. UTTZ, SR.
